UNITED STATES PATENT OFFICE.

GEORGE WASHINGTON KEMP, OF TALLAPOOSA, GEORGIA.

MOP-HEAD.

1,065,140.

Specification of Letters Patent.

Patented June 17, 1913.

Application filed August 19, 1912. Serial No. 715,805.

To all whom it may concern:

Be it known that I, GEORGE W. KEMP, a citizen of the United States, residing at Tallapoosa, in the county of Haralson and State 5 of Georgia, have invented certain new and useful Improvements in Mop-Heads, of which the following is a specification.

This invention relates to mop-heads, and its object is to provide a strong, simple 10 and durable device of this kind, and also one which is easy to handle, and which enables the mop to be quickly applied or removed.

With these objects in view, the invention 15 consists in a novel combination and arrangement of parts to be hereinafter described and claimed, reference being had to the accompanying drawing forming a part of this specification, in which drawing,

Figure 1 is a front elevation of the mop-head; Fig. 2 is an end view thereof, and Fig. 20 3 is an enlarged horizontal section on the line 3—3 of Fig. 1.

Referring specifically to the drawing, the 25 mop-head comprises stationary and movable jaws 5 and 6, respectively, between which the mop is clamped. The stationary jaw is a flat metal bar having at each end a depending guide-stem 7 for the movable jaw, the latter being also a flat metal bar which 30 extends between the guide-stems and has notches 8 in its ends in which notches the guide-stems fit. The movable jaw is parallel to the stationary jaw, and is slidable toward and from the latter on the guide- 35 stems.

The movable jaw is adjustable by means 40 of bolts 9 passing through alined apertures in the two jaws, near the ends thereof. The heads 10 of the bolt are enlarged on one side, and have in said side a notch 11 in which

the guide-stems 7 fit. On the upper end of each bolt is threaded a wing-nut 12 which screws down on the top of the jaw 5. From the jaw 5 extends a tang 13 for attachment of a suitable handle.

In operation, the mop is placed between the jaws 5 and 6, and the wing-nuts 12 are operated to slide the jaw 6 toward the jaw 5 until the mop is tightly clamped between said jaws. To remove the mop, it is necessary only to unscrew the wing-nuts and back the jaw 6 from the jaw 5. It will therefore be seen that the mop can be quickly applied or removed.

The device is simple in construction, 55 strong and durable, and it effectually serves the purpose for which it is designed. The bolt-heads 10 guide the bolts 9, and prevent rotation thereof, so that they may be drawn as described by operating the wing-nuts 12. 60 The position of the jaw 6 when it is clamping the mop is shown by dotted lines in Fig. 1.

I claim:

A mop-head comprising stationary and 65 movable jaws, guide-stems extending from the stationary jaw, between which guide-stems the movable jaw extends, said movable jaw having notches in its ends in which the guide-stems fit, bolts connecting the jaws, 70 the heads of the bolts being enlarged on one side and having therein notches in which the guide-stems fit, and nuts screwed on the bolts against one of the jaws.

In testimony whereof I affix my signature 75 in presence of two witnesses.

GEORGE WASHINGTON KEMP.
